US00D718300S

(12) **United States Design Patent**
Oakley

(10) **Patent No.:** **US D718,300 S**
(45) **Date of Patent:** **** Nov. 25, 2014**

(54) **MULTIPLE MODE DISPLAY DEVICE**

(71) Applicant: **Intel Corporation**, Santa Clara, CA (US)

(72) Inventor: **Nicholas W. Oakley**, Portland, OR (US)

(73) Assignee: **Intel Corporation**, Santa Clara, CA (US)

(57)

CLAIM

The ornamental design for a multiple mode display device, as shown and described.

DESCRIPTION

FIG. 1 is a perspective view illustrating a design for a multiple mode display device;

FIG. 2 is a front view thereof;

FIG. 3 is a back view thereof;

FIG. 4 is a side view thereof;

FIG. 5 is another side view thereof;

FIG. 6 is a top view thereof; and,

FIG. 7 is a bottom view thereof.

The broken lines shown in the drawings illustrate portions of the multiple mode display device and form no part of the claimed design.

1 Claim, 5 Drawing Sheets
